United States Patent Office

Des. 218,719
Patented Sept. 15, 1970

218,719

TRAFFIC BARRIER

Louis H. Peters, Somerville, N.J., assignor to Union
Carbide Corporation, New York, N.Y., a corporation
of New York

Filed June 6, 1969, Ser. No. 17,561

Term of patent 14 years

Int. Cl. D29—99

U.S. Cl. D72—1

F/G. 1

FIG. 2

FIG. 3

FIG. 4

FIG. 1 is an elevated isometric view of a traffic barrier showing our new design;

FIG. 2 is a side plan view of the traffic barrier of FIG. 1;

FIG. 3 is a side plan view of the traffic barrier of FIG. 1 taken at a 90° angle from FIG. 2; and

FIG. 4 is a bottom plan view of the traffic barrier of FIG. 1.

I claim:

The ornamental design for a traffic barrier, substantially as shown and described.
